UNITED STATES PATENT OFFICE.

HUGO A. KNOS, OF BELLEVUE, OHIO.

DUST-COLLECTOR.

No. 909,425.

Specification of Letters Patent.

Patented Jan. 12, 1909.

Application filed May 25, 1902. Serial No. 434,926.

To all whom it may concern:

Be it known that I, HUGO A. KNOS, a citizen of the United States, residing at Bellevue, in the county of Huron and State of Ohio, have invented certain new and useful Improvements in Dust-Collectors, of which the following is a specification, reference being had therein to the accompanying drawings.

- 10 This invention relates to dust collectors, and is designed more particularly for use in connection with polishing apparatus for plows, steel shovels and similar articles. Plow castings and articles of this character 15 are usually polished by means of an abrasive wheel and the operation produces great quantities of dust which is not only very disagreeable, but is injurious to the health of the operator.
- 20 The object of the present invention is to provide means for collecting this dust and removing the same without in any manner interfering with the operation of the polishing apparatus, thereby entirely eliminating 25 the disagreeable and unhealthful features of the work.

With this object in view my invention consists in certain novel features of construction and in certain parts and combinations hereinafter to be described, and then more particularly pointed out in the claims.

In the accompanying drawings, Figure 1 is a longitudinal sectional view, taken centrally through a dust collector embodying 35 my invention; Fig. 2 is a front elevation of the same; and Fig. 3 is a detail view of the movable support for the rack.

In these drawings I have illustrated the preferred form of my invention and have 40 shown the same as comprising a casing or receptacle 1 mounted on suitable supports 2 and having one end open and the top, bottom and sides thereof closed. Mounted near the open end of the receptacle is the usual 45 abrasive wheel 3 which is carried by a shaft 4, which, in turn, is supported in the usual manner.

The receptacle 1 may be of any suitable construction and shape, but I prefer to construct the same of sheet metal and to form the same rectangular in cross section with its side walls converging away from the open end thereof.

The receptacle is provided with a suitable 55 outlet 5, to which is connected a suction pipe 6, by means of which a suction is created

within the receptacle 1. This outlet 5 may be arranged at any suitable point in the casing, but I have, in the present instance, shown the same as formed in the top wall of 60 the casing and near the smaller end thereof.

A hood or guard 7 is mounted on the top wall of the casing near the open end thereof and extends about the upper side of the abrasive wheel 3. This guard or hood 7 preferably has one of its side walls hinged, as shown at 8, to permit the same to be swung outwardly when it is desired to remove the abrasive wheel from the shaft 4 or to mount the same thereon.

The casting or other work which it is desired to polish is supported against the lower side of the abrasive wheel 3 by means of a work-holder or rack 9 which is movably mounted beneath the same. To enable all 75 portions of the work to be brought into engagement with the abrasive wheel 3, it is necessary that the supporting rack 9 should be capable of lateral, longitudinal and vertical movements relatively to the abrasive 80 wheel and should also have a rotary movement about its longitudinal axis, thus enabling the work to be turned at any desired angle to the wheel. To this end I have provided a rack, one end of which is adapted to 85 extend into the receptacle 1 and which is so mounted as to enable the same to have the necessary movements relatively to the abrasive wheel. This is preferably accomplished by providing a suitable guide within the receptacle 1, upon which there is mounted a support for the end of the rack 9, and, in the present instance, I have shown this guide as a double track comprising bars 10 supported from the top wall of the casing 1 by means of 90 depending arms or supports 11 and adapted to support a roller carrier or truck 12 having a depending arm or bar 13 provided with one or more apertures 14 adapted to receive a rod 15 at the forward or inner end of the 100 rack 9. This rod is of a slightly smaller diameter than the aperture 14 and is retained therein in any suitable manner, as by means of a key 16. Thus, it will be seen that the rack can be moved about the pivotal center 105 formed at the point of support of the rod 15 on the bar 13 in either a vertical or a lateral direction, or it can be turned about its longitudinal axis. Further, it will be apparent that free longitudinal movement of the rack 110 is permitted by the movable support or roller carrier 12 which travels freely upon

the double track; and also, that the rack can be adjusted vertically of the casing by inserting the rod 15, carried by the rack, in different apertures 14 of the bar 13.

- 5 In the operation of the device the abrasive wheel is rotated at a high rate of speed in the direction indicated by the arrow, and, the work being supported against the lower edge thereof, it will be apparent that the dust will 10 be thrown from the wheel and from the work in the direction of the receptacle where it is taken up by the suction created within the receptacle and discharged through the outlet pipe 6. This suction being of sufficient 15 strength to take up the dust at the point of contact of the wheel with the work and the hood 7 preventing any particles of dust or material which may adhere to the wheel from being thrown off the upper edge thereof, it 20 will be seen that all the dust will be taken up by the collector and that none of the same will be permitted to escape. Further, it will be seen that the supporting rack for the work is so mounted as to enable the abrasive 25 wheel to be supported close to the open side of the receptacle 1, and, at the same time, to allow the rack the necessary movement to enable all parts of the work to be brought into engagement with the abrasive wheel. 30 A further advantage accruing from the use of my dust collector is that it enables the abrasive material or emery dust, which is removed from the abrasive wheel, to be collected and again used either in the manufacture 35 of other abrasive wheels or an abrasive powder or dust. By thus collecting the emery dust a considerable saving is made in the cost of the operation of the polishing apparatus.
- 40 I wish it to be understood that I do not desire to be limited to the details of construction shown and described, for obvious modifications will occur to a person skilled in the art.
- 45 Having thus fully described my invention, what I claim as new and desire to secure by Letters Patent, is:—
1. A device of the character described comprising an abrasive wheel, a dust-receiving receptacle supported in the rear of said wheel, and a work-support mounted near said receptacle and adapted to be moved toward and away from the lower edge of said wheel and transversely to its axis of rotation.
- 50 2. A device of the character described, comprising an abrasive wheel, a dust-receiving receptacle supported near said wheel, a work-support mounted near said receptacle with one end extending into the same and 55 adapted to be moved toward and away from said wheel and transversely to its axis of rotation.
3. A device of the character described comprising an abrasive wheel, a dust-receiving receptacle supported near said wheel, and

a work-support having one end movably mounted within said receptacle.

4. A device of the character described comprising an abrasive wheel, a dust-receiving receptacle supported near said wheel, a work-support having one end movably mounted within said receptacle, and means for creating a suction within said receptacle. 70

5. A device of the character described comprising an abrasive wheel, a dust-receiving receptacle supported near said wheel, a work-support, a guide within said receptacle, means for movably supporting said work-support upon said guide, and means for creating a suction within said receptacle. 75

6. A device of the character described comprising an abrasive wheel, a dust-receiving receptacle supported near said wheel, a work-support, a track supported within said receptacle, a carrier movably mounted on said track, a supporting member carried by said carrier, means for connecting said work-support to said supporting member, and means for creating a suction within said receptacle. 80

7. A device of the character described comprising an abrasive wheel, a dust-receiving receptacle supported near said wheel, a work-support, a track supported within said receptacle, a roller carrier mounted on said track, an apertured bar extending from said carrier, a rod secured to said work-support and adapted to extend through the aperture in said bar, means for retaining said rod within said aperture, and means for creating a suction within said receptacle. 90

8. A device of the character described comprising an abrasive wheel, a dust-receiving receptacle supported near said wheel, a suction pipe connected to that end of the receptacle removed from said wheel, a work-support, a track supported from the upper wall of said receptacle, a roller carrier mounted on said track, a supporting bar depending from said roller carrier and having a series of apertures therein, a rod secured to one end of said work-support and adapted to enter any one of said apertures, and means for securing said rod within said aperture. 105

9. A device of the character described comprising a receptacle having one end open and its side walls converging away from said open end, an abrasive wheel mounted near the open end of said receptacle, a work-holder, a guide within said receptacle, a movable support mounted on said guide, means for loosely connecting one end of said work-holder to said movable support, and means located near the small end of said receptacle for creating a suction therein. 115

10. A device of the character described comprising a receptacle having one end open and its side walls converging away from said open end, an abrasive wheel mounted near the open end of said receptacle, a work- 120

holder, a guide within said receptacle, a movable support mounted on said guide, means for loosely connecting one end of said work-holder to said movable support, means located near the small end of said receptacle for creating a suction therein, and a hood carried by said receptacle and extending over said abrasive wheel.

11. A device of the character described comprising a receptacle having one end open and its side walls converging away from said open end, an abrasive wheel mounted near the open end of said receptacle, a work-holder, a guide within said receptacle, a movable support mounted on said guide, means for loosely connecting one end of said work-holder to said movable support, means located near the small end of said receptacle for creating a suction therein, and a hood car-

ried by said receptacle and extending over 20 said abrasive wheel, said hood having one of its side walls hinged thereto.

12. A device of the character described comprising an abrasive wheel, a dust-receiving receptacle supported near said wheel, and 25 a work-support pivotally mounted near said receptacle.

13. A device of the character described comprising an abrasive wheel, a dust-receiving receptacle supported near said wheel, and 30 a work-support having one end pivotally mounted within said receptacle.

In testimony whereof, I affix my signature in presence of two witnesses.
